UNITED STATES PATENT OFFICE.

MYER METZGER, OF CHICAGO, ILLINOIS.

FOOD-DISPLAY COVER.

Application filed September 21, 1922. Serial No. 589,608.

To all whom it may concern:

Be it known that I, MYER METZGER, a citizen of the United States, residing at Chicago, in the county of Cook and State of Illinois, have invented certain new and useful Improvements in Food-Display Covers, of which the following is a specification.

Heretofore it has been customary to place over a receptacle containing food or other articles to be displayed, a transparent cover embodying one or more hinged sections, and in order to maintain the cover in position when the container is inclined or stands uprightly on one side, it has been customary to provide a fastening device adapted to be applied to the container and cover, but this form of fastening device is objectionable because oftentimes the fastening device is misplaced or lost. In other instances fastening screws have been employed which were passed through apertures in the frame of the cover and into the body of the receptacle or container, thereby necessitating the employment of tools for both the application and removal of the fastening device.

To overcome all of these objections and difficulties and to provide an improved food display cover of this character which will be of a sanitary nature and which is provided with a flanged portion adapted to engage over the edge of the container or receptacle, and which cover has associated or connected therewith a fastening device whereby the cover may be readily applied and as readily removed without necessitating the employment of any tools, is one of the objects of the present invention.

A further object is to provide an improved hinge for connecting the sections of the cover and which hinge has associated therewith a fastening device adapted to co-operate with the wall of the receptacle or container for detachably but securely fastening the cover in position.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention and in which—

Figure 1 is a perspective view of a con-

tainer having a cover constructed in accordance with the principles of this invention applied thereto.

Figure 2 is an enlarged detail sectional view taken on line 2—2, Figure 1.

Figure 3 is a side elevation of the hinge connection between the cover sections.

Figure 4 is a top plan view of Figure 3.

Figure 5 is a detail sectional view on line 5—5, Figure 3.

Figure 6 is a detail perspective view of a modified form of fastening device.

Referring more particularly to the drawing, the numeral 10 designates generally a receptacle or container of a box-like formation for containing the articles to be displayed.

The cover, and as shown in the present form of the invention, embodies two sections 11 and 12, formed of any suitable material preferably metal, and these cover sections are of such a size and configuration that when placed in position upon the receptacle 10, will close the open side thereof. Each of the sections 11 and 12 is provided with flanges 13—14, adapted to engage over the sides and ends of the receptacle. Each section is preferably of a frame-like construction adapted to receive a transparent member 15, such as glass, the glass being preferably held in position by substantially L shaped members 16, which engage and rest upon the glass adjacent its edge and also engage and rest against the respective flanges 13—14 of the respective cover sections. The edge 17 of the flange of the cover sections is bent over one edge of the members 16 for securing the latter in position and thereby operates to hold the glass or transparent member 15 secured to the cover section.

The cover sections are connected together by means of a suitable hinge secured on the opposite edges of the sections. This hinge consists of two members 18—19, one of which is secured to each of the cover sections and the hinge sections 19 are pivotally connected by means of a pivot pin 20. The cover thus formed is adapted to rest upon the receptacle 10, and when the receptacle is arranged in an inclined position or is stood upright upon one of its side edges, the flanges 13 and 14 will hold the cover against sliding with respect to the receptacle.

Pivotally connected with one of the hinge

sections, preferably the section 18 and more particularly to a flanged portion 21 thereof, is a fastening device 22, the latter being secured to the flanged portion 21 by means of a pivot pin 23. One portion of the fastening device 22 is shaped to form a handle 24, while another portion 25 is shaped to form a projection, preferably of a cam-like configuration and extends for a considerable distance beyond the pivot 23 and also beyond the hinge member 18, when the fastening device 22 is moved in one direction about its pivot. The projecting edge 25 of the fastening device is preferably of a comparatively thin construction so as to form a cutting edge adapted to cut into the wall of the receptacle 10 as at 26, when the fastening device 22 is moved into the positions shown in Figures 3, 4 and 5.

Connected preferably with the flanged portion 21 of the hinge member 18 is a depending projection 27 and the fastening device 22 is constructed of material which is preferably slightly flexible. The projection 27 is such that when the fastening device 22 is moved about its pivot 23, so as to cause the portion 25 to embed itself in the wall of the receptacle 10, it will engage the upper surface of the fastening device 22 and depress the latter until the handle 24 assumes a position to permit the projection 27 to pass behind the fastening device, thereby locking the fastening device in its adjusted position. When it is desired to unfasten or release the cover so as to detach it from the receptacle, the handle 24 of the fastening device is depressed slightly until the end of the projection 27 is cleared, after which the fastening device may be moved about its pivot in a direction to release the cover.

If desired an elastic member 28 preferably in the form of a coil spring is connected as at 29 with the hinge member 19 and as at 30 with the hinge member 18. This elastic member tends to hold the swinging cover section in a closed position but will yield sufficiently to permit the cover section 12 to be moved about its pivot to permit access to the interior of the receptacle 10.

In the form of the invention shown in Figure 6, the flanged section 21 is provided with a depending portion 31, having an extended edge or surface 32, which is adapted to engage the upper surface of the fastening device 22. This edge 32 of the depending portion 31 is of a length so as to permit the edge 32 to always remain in contact with the upper surface of the fastening device 22 in any position of the latter and serves to depress the fastening device 22 with respect to the pivot 23 so as to cause a binding action of the fastening device 22 upon its pivot and thereby lock the fastening device against accidental movement about its pivot.

With this improved construction it will be

manifest that the cover may be readily applied and as readily removed from the receptacle and when the fastening device 22 is in a position to secure the cover to the receptacle, the cover will be held against accidental displacement even though the receptacle is disposed in an inclined position or is stood upright upon one of its side edges, and it will be manifest that the device is always in condition for use and may be applied to or removed from the receptacle without necessitating the use or employment of any tools for such purpose. The fastening device being permanently connected with one of the hinge members will always be in position for use.

While the preferred forms of the invention have been herein shown and described it is to be understood that various changes may be made in the details of construction and in the combination and arrangement of the several parts, within the scope of the claims, without departing from the spirit of this invention.

What is claimed as new is:—

1. In combination, an open receptacle, a cover therefor, circumferential flanges on the cover for engaging over the edges of the receptacle, said cover embodying a hinged section, and means embodying a pivotally mounted clamping device connected with the cover for securing the cover to the receptacle.
2. In combination, an open receptacle, a cover therefor, said cover embodying sections, a hinge connecting the sections, and freely shiftable means connected with one of the hinge members and adapted to engage a wall of the said receptacle for securing the cover in position.
3. In combination, an open receptacle, a cover therefor, said cover embodying sections, a hinge connecting the sections, and a clamping device pivotally connected with one of the hinge members and adapted to engage a wall of the said receptacle for securing the cover in position.
4. In combination, an open receptacle, a cover therefor, said cover embodying sections, a hinge connecting said sections, and a securing device pivotally connected with one of the hinge members for securing the cover in position, a portion of said securing device being adapted to be embedded in the wall of the receptacle as said device is moved in one direction about its pivot.
5. In combination, an open receptacle, a cover therefor, said cover embodying sections, a hinge connecting said sections, a securing device pivotally connected with one of the hinge members for securing the cover in position, a portion of said securing device being adapted to be embedded in the wall of the receptacle as said device is moved in one direction about its pivot, and means for restraining the clamping device against move-

ment in one direction and under normal conditions.

6. In combination, an open receptacle, a cover therefor, said cover embodying sections, a hinge connecting said sections, a securing device pivotally connected with one of the hinge members for securing the cover in positon, a portion of said securing device being adapted to be embedded in the wall 10 of the receptacle as said device is moved in one direction about its pivot, and means for restraining the clamping device against movement in one direction and under normal conditions, the said means being adapted 15 to yield when said clamping device is moved in the opposite direction under abnormal conditions.

7. In combination, an open receptacle, a cover therefor, said cover embodying sections, a hinge connecting said sections, and a securing device pivotally connected with one of the hinge members and adapted to co-operate with the receptacle to exert a clamping action for detachably securing the cover 25 upon the receptacle.

8. In combination, an open receptacle, a cover therefor, said cover embodying sections, a hinge connecting said sections, a securing device pivotally connected with one 30 of the hinge members and adapted to co-operate with the receptacle to exert a clamping action for detachably securing the cover upon the receptacle, and means co-operating with the said securing device for restraining 35 its movement in one direction.

9. In combination, an open receptacle, a cover therefor, said cover embodying sections, a hinge connecting said sections, a securing device pivotally connected with one 40 of the hinge members and adapted to co-operate with the receptacle to exert a clamping action for detachably securing the cover upon the receptacle, and means carried by one of the hinge members and co-operating

with the said securing device for yieldingly 45 restraining the latter against operation.

10. In combination, an open receptacle, a cover therefor, said cover embodying sections, a hinge connecting said sections, a securing device pivotally connected with one 50 of the hinge members and adapted to co-operate with the receptacle to exert a clamping action for detachably securing the cover upon the receptacle, and a projection on one 55 of the hinge members adapted to co-operate with the securing device for locking the latter.

11. In combination, an open receptacle, a cover therefor, said cover embodying sections, a hinge connecting said sections, a securing device pivotally connected with one 60 of the hinge members and adapted to co-operate with the receptacle to exert a clamping action for detachably securing the cover upon the receptacle, and a surface connected 65 with one of the hinge members and adapted to engage and deflect the locking device to create a binding action upon the pivot of said device.

12. In combination, an open receptacle, a 70 cover therefor, said cover embodying sections, a hinge connecting said sections, a securing device pivotally connected with one of the hinge members and adapted to co-operate with the receptacle to exert a clamping 75 action for detachably securing the cover upon the receptacle, and a surface connected with one of the hinge members and adapted to engage and deflect the locking device to create a binding action upon the pivot of 80 said device, a portion of said surface being adapted to engage behind the locking device for yieldingly restraining movement of said device in one direction about its pivot.

In testimony whereof I have signed my 85 name to this specification, on this 12th day of September, A. D. 1922.

MYER METZGER.
